(57) **CLAIM**

The ornamental design for an ice cream maker kitchen mixer attachment, as shown and described.

DESCRIPTION

FIG. 1 is an exploded perspective view of an ice cream maker kitchen mixer attachment of our new design; FIG. 2 is a prospective view of the invention inserted into a kitchen mixer thereof;

FIG. 3 is a side prospective view thereof;

FIG. 4 is a bottom prospective view thereof;

FIG. 5 is an enlarged prospective view of the invention with a lid exploded from a bowl thereof; and, FIG. 6 is a top prospective view of the invention with the lid exploded from the thereof.

The broken lines shown in the drawing are for illustrative purposes only and form no part of the claim design.
